UNITED STATES PATENT OFFICE.

MAURITS J. SANDIN, OF WILKINSBURG, PENNSYLVANIA, ASSIGNOR TO WESTINGHOUSE ELECTRIC & MANUFACTURING COMPANY, A CORPORATION OF PENNSYLVANIA.

REFILLABLE FUSE.

Application filed July 5, 1918. Serial No. 308,686.

To all whom it may concern:

Be it known that I, MAURITS J. SANDIN, a citizen of the United States, and a resident of Wilkinsburg, in the county of 5 Allegheny and State of Pennsylvania, have invented a new and useful Improvement in Refillable Fuses, of which the following is a specification.

My invention relates to fuses and particularly to refillable cartridge fuses.

One object of my invention is to provide means for ventilating a cartridge fuse to prevent damage thereto by gas pressure, and for cooling the escaping gases to prevent 15 damage to surrounding objects.

Another object of my invention is to provide a fuse cartridge that shall have relatively-movable automatic means for regulating the escape of arc gases in accordance 20 with the pressure of the gases.

Another object of my invention is to provide a cartridge fuse that shall have means for compensating for filling deposits in a gas-escape passage to insure the escape of 25 the gases.

A further object of my invention is to provide a novel and effective gas-tight joint between certain members of a refillable fuse cartridge.

In practicing my invention, I provide a refillable-cartridge fuse having automatic ventilating and cooling means that operates, in accordance with the gas pressure, to regulate the escape of gas and means for compensating for filling deposits in certain 35 ventilating paths to maintain said paths open.

I further provide a novel combination of old expedients to provide a new and effective 40 gas-tight joint therein.

Figure 1 of the accompanying drawings is a side view, partially in elevation and partially in section, of a refillable-cartridge fuse embodying my invention, Fig. 2 is a 45 transverse sectional view of a ferrule therefor, taken along the line II-II of Fig. 1, and Fig. 3 is a detail view of a modified form of washer embodied in my invention.

In general, my device comprises a tubular 50 casing 1, of fiber or other suitable insulating material, threaded metal end rings or collars 2 thereon for the reception of internally-threaded metal ferrules 3, a fusible element 4, and metal washers 5 for supporting

the ends of the element 4 and engaging the outer end of the collar 2.

The collars 2, having interiorly and exteriorly threaded portions 6 and 7, respectively, of different diameters and surrounding exteriorly threaded and reduced portions 8 and 9 of the casing 1, are initially advanced to operative positions in gas-tight relation to the casing 1 where they are rigidly and permanently held by rivets 10. This is a materially better arrangement than where the collar is both threaded and cemented in position, as the cement will fail when sufficient twisting force is applied.

Each ferrule 3 has an interiorly-threaded portion 11 of one diameter adjacent its open end and two plain portions 12 and 13 of successively smaller diameters relatively closely fitting a perforate metal washer 14 and a relatively loosely fitting imperforate insulating washer 15, respectively. When the ferrule 3 is advanced toward the casing 1 on the collar 2, the washer 14 engages and tightly wedges the end of the element 4 against the washer 5 to provide a good conducting path from the element 4 to the members 2 and 3.

The end wall 16 of the ferrule 3 has an opening or openings 17 and an inner surface having a knurled portion or grooves 18 that direct the gases from the perimeter of the portion 13 to the opening 17.

The washer 15, preferably of a relatively hard and dense insulating material, such as fiber, fuller-board or other suitable material that may be slowly consumed or scored by arc gases along lines opposite and following the grooves 18, is relatively loosely disposed between the wall 16 and the washer 14 and is thereby permitted a relatively small amount of movement along its axis.

The escaping gases, caused by volatilization of the element 4, are directed through the openings in the washers 5 and 14, outwardly around the washer 15 and inwardly toward the opening 17. If the pressure of the gas is relatively high, the washer 15 will be accordingly automatically pressed forcibly against the wall 16 to cause the gases to escape principally through the grooves 18. If the pressure of the gases is relatively slight, and, therefore, less likely to carry flame a considerable distance, the washer 15 will be pressed by a smaller force, thereby permitting the gases to escape more

freely and not necessarily entirely through the grooves 18.

Successive operations of the device will gradually cause a filling deposit of combustion products, such as volatilized metal, to accumulate upon the sides of the grooves 18. As compensation for this condition, the washer 15 will char and gradually be indented along surfaces opposite the grooves 18, thus automatically maintaining open paths for the escape of gases.

As shown in Fig. 3, the washer 15 may be grooved instead of the ferrule 3.

The device prevents the escape of flame therefrom, gives sufficient ventilation to prevent damage to its structure by explosive forces therein, is simple and economical in construction, and easy to manipulate. The arrangement, by which the ring 2 is both threaded and riveted to the casing 1, is a combination of old expedients which, to the best of my knowledge, has not been employed in a similar manner for a similar purpose, that is, to provide large lightly-engaging surfaces reduced to occupy slight space, as is accomplished by having the engaging surfaces threaded to prevent the passage of gases therebetween, and that may not be readily separated or disturbed in this relation.

While I have shown and described particular forms of my invention, changes may be effected therein without departing from the spirit and scope thereof, as set forth in the appended claims.

I claim as my invention:

1. A cartridge fuse comprising a member having a groove and a consumable member adjacent said groove to form a gas path, said consumable member to be consumed along a line following said groove to compensate for a filling deposit therein, caused by the operation of said fuse, to maintain a path similar to said first path.

45 2. A cartridge fuse comprising a tubular casing, an end ferrule having a centrally-disposed opening in its transverse wall and a discoidal washer disposed in direct contact with the surface of the said wall to direct arc gases radially between the wall and the said washer toward said opening.

3. A cartridge fuse comprising a tubular casing, an end ferrule having a transverse wall provided with an opening and a relatively movable pressure-responsive washer disposed in direct contact with the surface of the said wall and over said opening for preventing the passage of escaping gases to the said opening except between the wall and the washer and adapted to be pressed into more intimate contact with the said wall by the arc gases within the casing.

4. A cartridge fuse comprising a tubular casing having a transverse closure wall provided with a perforation and a relatively

movable pressure-responsive washer disposed in direct contact with the surface of the said wall and over said openings for preventing the passage of escaping gases to the said opening except between the wall and the washer and adapted to be pressed into more intimate contact with the end wall by arc gases.

5. A cartridge fuse comprising a tubular casing having a transverse wall provided with an opening and a washer consumable by arc gases passing to the said opening, the said washer being disposed in direct contact with the said wall and covering the said opening.

6. A cartridge fuse comprising a tubular casing and an end ferrule having a transverse wall provided with an opening and a groove leading to said opening.

7. A cartridge fuse comprising a tubular casing, an end ferrule having an opening and grooves leading to said opening in its transverse wall and a washer disposed over said opening and said grooves.

8. A cartridge fuse comprising a tubular casing, an end ferrule having an opening and grooves leading to said opening in its transverse wall, an insulating washer disposed over said opening and said grooves, and a conducting washer disposed over said insulating washer.

9. A cartridge fuse comprising a tubular casing, an end ferrule having an opening and radial grooves leading to said opening in its transverse wall, an insulating washer disposed over said opening and said grooves and a perforate conducting washer disposed over said insulating washer.

10. In a cartridge fuse, the combination with a casing, of an end member therefor having an apertured wall, and a member having a surface disposed adjacent the surface of said wall, one of said members having a groove in its surface adjacent the other member and cooperating therewith to form a gas-escape passage.

11. In a cartridge fuse having a casing, a pair of closure members having contiguous surfaces, one of which is provided with a groove forming a channel between the members leading to an opening in one of the members whereby arc gases within the casing are conducted between the said members to the atmosphere.

12. In a cartridge fuse having a casing, a pair of closure members having contiguous surfaces, one of which is provided with a groove forming a channel between the members and establishing communication between the interior of the casing and an opening in one of the members.

13. In a cartridge fuse having a casing, a pair of closure members having contiguous surfaces, one of which is provided with a groove forming a channel between the mem-

- bers and establishing communication between the interior of the casing and an opening in one of the members, one of the said members being formed of material that is consumable by the heated gases along the line of the said groove.
14. In a cartridge fuse having a casing, a pair of closure members having transverse contiguous surfaces, one of which is provided with a groove forming a channel between the members and establishing communication between the interior of the casing and an opening in one of the members.
15. In a cartridge fuse having a casing, a pair of closure members having transverse contiguous surfaces, one of which is provided with a groove forming a channel between the members and communicating with an opening in one of the said members.
16. In a cartridge fuse having a casing, a pair of closure members having transverse contiguous surfaces, one of which is provided with a groove extending from a point adjacent the periphery thereof to an opening in one of the members.
17. In a cartridge fuse, the combination with a vented wall member having a groove leading to a vent therein, of a valve covering the vent and the groove made of consumable material adapted to be partially consumed by the heated arc gases passing through the groove to the vent.
18. In a cartridge fuse having a casing, a pair of closure discs placed face to face, one of the members being provided with an opening therethrough and the adjacent face of one of the members having portions in different planes whereby portions of the said disc are held out of contact by the remaining portions to provide a passage for gases between the said discs from or to the said opening.
19. In a cartridge fuse having a casing, a pair of closure discs placed face to face, the adjacent face of one of the members being provided with portions in different planes whereby portions of the disc are held out of contact by the remaining portions which engage the other disc to provide a passage between the discs for escaping gases.

In testimony whereof, I have hereunto subscribed my name this 28th day of June, 1919.

MAURITS J. SANDIN.
